UNITED STATES PATENT OFFICE.

THOMAS AUGUSTINE LEE, OF ESSENDON, MELBOURNE, VICTORIA, AUSTRALIA.

FUSE-BOX.

1,382,989.

Specification of Letters Patent. Patented June 28, 1921.

Application filed February 9, 1920. Serial No. 357,318.

To all whom it may concern:

Be it known that I, THOMAS AUGUSTINE LEE, electrical fitter, a subject of the King of Great Britain and Ireland, and a resident 5 of the postal district of Ascot Vale, in the city of Essendon, a suburb of the city of Melbourne, in the county of Bourke, State of Victoria, Commonwealth of Australia, (whose post-office address is 50 Filson 10 street, in the said postal district of Ascot Vale,) have invented certain new and useful Improvements in Fuse-Boxes, of which the following is a specification.

This invention relates to closed fuse boxes 15 of the kind wherein visible indication is given externally of the fuse box upon an internally disposed fuse wire breaking. The invention aims at providing a fuse box of this character in which a glance suffices to 20 show which fuse box of a number requires renewal of the fuse wire, and in which automatic intimation positively occurs upon a fuse wire being severed. The manner of indication is such that it cannot escape notice 25 even under casual examination and consequently identification of the relative fuse box may be instantly effected without internal inspection of a number of boxes as has frequently been the case hitherto. Further, all electrified parts are totally 30 closed.

The invention more particularly resides in a pivoted spring controlled lever retained within the box by the fuse wire thereof and 35 adapted when liberated through melting of the fuse wire to project beyond the cap of the box under the influence of the spring. It further consists in details of construction and combinations of parts as pointed out in 40 the appended claims.

Referring to the drawings which form part of this specification:—

Figure 1 is a plan of a base piece; terminals and contacts are removed for convenience of illustration.

Fig. 2 is a section on the irregular line A—A, Fig. 1.

Fig. 3 is a view of a tubular terminal and contacts associated therewith, the parts being separated for convenience of illustration.

Fig. 4 is a plan of the group of parts seen in Fig. 3.

Fig. 5 is a central longitudinal section of the base piece; contacts are in position.

Fig. 6 is a side elevation of a cap. Contact tongues, the fuse wire, a pivoted lever,

and other parts are omitted for convenience of illustration.

Fig. 7 is an inverse plan of Fig. 6, that is, looking in the direction of the arrow or 60 with the cap overturned.

Fig. 8 is a side elevation of the cap looking at the opposite side to that seen in Fig. 6.

Fig. 9 is a view of a group of parts comprising a lever, pivot pin, spring and holding ring all separated for convenience of 65 illustration.

Fig. 10 is a central longitudinal section of a cap with the pivoted lever, contact tongues and other parts in place.

Fig. 11 is a side elevation of a fuse box according to the invention. The fuse wire is broken allowing the indicator to project 70 outside the cap.

Fig. 12 is an enlarged detail view of a holding screw by rotation of which the tension of the fuse wire may be increased.

Fig. 13 is a central cross section of Fig. 11, the indicator being held in normal position by the fuse wire.

This invention includes a base piece 2 having formed near each of its ends a retention screw hole indicated at 3. Formed in the base piece near each end thereof is also a nut recess indicated at 4. Passing from each nut recess is a terminal hole indicated at 5. Above each terminal hole and in communication therewith is a terminal cavity indicated at 6. Passing from each cavity 6 is a contact pocket indicated at 7 and having 90 alining shoulders 8. Formed in or extending from each terminal cavity 6 is a screw niche indicated at 9. Upstanding from each side of the base piece is a flange 10. The base piece may be formed of any suitable insulating material.

Disposed in each terminal cavity 6 is a metallic tubular terminal 11 having a reduced threaded shank 12 forming a shoulder 13. The shank is accommodated in the terminal hole 5 in communication with the cavity. Threaded upon the shank of each terminal is a retaining nut 14. The nuts 14 are accommodated in the nut recesses 4. Carried by or threaded into each terminal 11 is 105 an inclined holding screw 15.

With each tubular terminal is used a metallic contact comprising an inner and an outer element. Each element consists of a bottom portion 16 having therein a hole, indicated at 17, through which passes the reduced threaded shank 12 of the relative ter-

minal 11. Upstanding from each bottom portion 16 is a flange 18 having a down-turned spring lip 19. Formed in each lip 19 is a slotway or sawcut, indicated at 20, there-
 5 by bifurcating the lip to improve the contact. It will be seen that one bottom portion 16 is longer than the other thereby pro-
 viding a tongue space, indicated at 21, be-
 tween the spring lips 19. Formed in the
 10 bottom portion of one of the elements is an indentation indicated at 22. The bottom portion 16 of the other element is provided with a projection 23 engaging in the indentation 22 and thereby retaining the inner and
 15 outer elements in fixed relationship with the spring lips 19 spaced apart.

In combination with the foregoing is used a cap 25 having formed in each of its sides an external finger groove indicated at 26.
 20 The cap may be formed of any suitable non-conducting material. Formed through the top or crown of the cap 25 is an indicator slotway shown at 27. The slotway commu-
 nicates with a lever chamber indicated at 28.
 25 Portion of each side of the cap 25 is cut away as at 29 to accommodate the upstand-
 ing flanges 10 of the base piece 2. Formed in the cap 25 at each end thereof is a terminal cavity indicated at 30. Each cavity is
 30 provided with a screw niche indicated at 31. Formed in the cap 25 at or near each end thereof is also a tongue pocket indicated at 32. Adjacent one of the tongue pockets is a pair of lugs 33 forming a spring recess, in-
 35 dicated at 34. Extending between the lugs 33 is a bearing shoulder 35. The spring re-
 cess is provided with an upper or inclined limit wall 37 to limit the movement of the pivoted lever hereinafter described. Ad-
 40 joining the other tongue pocket 32 is a fuse wire bearing lug 38 to minimize the sag of the fuse wire hereinafter described.

Disposed within each of the tongue pock-
 ets 32 is a metallic contact tongue 40. Each
 45 tongue is retained within its pocket by a holding screw 41 carrying a washer 42. Ex-
 tending between the holding screws and re-
 tained thereby is a fuse wire 43. If desired,
 one of the screws 41 may have serrations 44
 50 formed beneath its head whereby upon ro-
 tating the screw the fuse wire will be gripped and wound taut.

Extending between the lugs 33 and across the spring recess 34 is a pivot pin 45. Piv-
 55 oted to the pin 45 is the inner end of a lever 46 the outer end of which carries a triangu-
 lar indicator 47. The lever and indicator may be formed of any suitable non-conduct-
 ing material. Carried by the lever 46 is
 60 also a holding ring 48. Encircling the pivot pin 45 and disposed within the recess 34 are the coils 49 of a spring having bearing arms 50 extending in opposite directions from the said coils.

65 With this invention the triangular indi-

cator 47 is pushed inwardly into the cap 25. One end of a fuse wire is wound or twisted around the shank of one of the screws 41, the other end of the wire being passed through the holding ring 48 of the lever 46 and then 70 wound or turned around the other holding screw 41. The cap is now placed in position upon the fuse box base 2 the contact tongues 40 passing into the tongue spaces 21 of the contacts of the base piece. Upon 75 the fuse wire breaking it is obvious that the lever 46 and triangular indicator 47 will immediately swing outwardly through the slotway 27 under the influence of the spring coils 49. An inspection of a batch of fuse boxes will at once show in which fuse box renewal of the fuse wire is required as the indicator 47 will be quickly seen. Spare caps may be carried and substitution effected thereby dispensing with the necessity of 80 an electrician's services to fit a new fuse wire immediately.

Having now described my invention what I claim as new and desire to secure by Letters Patent is:—

90 1. A fuse box having spaced terminal contacts, a cover having connecting members to engage said contacts, a fuse strip extended between said connecting members, a lever pivotally mounted in a recess formed in the cover, means depending from the lever and encircling the fuse strip intermediate the connections, and a spring for projecting the lever in part above the cover under the influence of the spring on the separation of the 95 fuse strip.

100 2. A fuse box comprising a base, a cover therefor formed with a recess extending through the upper surface of the cover, a fuse strip removably secured in said cover, a lever pivotally mounted in said recess, a spring for actuating the lever to project a portion of said lever through the recess and above the upper surface of the cover, and a loop depending from the lever to receive the 110 fuse strip, the connection of the loop and fuse strip holding the lever withdrawn against the influence of the spring.

115 3. A fuse box including a base, a cover removably secured thereto, said cover being formed with a recess opening through the upper surface of the cover, a lever pivotally supported in the cover and having a signal indicating end adapted in operation to pass through the recess and project above 120 the upper surface of the cover, a spring connected to the lever and adapted to move it to operative position when free to act, and means carried by the lever to engage the fuse strip in the cover to hold the lever 125 normally against the influence of the spring.

In testimony whereof I affix my signature.
 T. A. LEE.

Witness:

CECIL M. LE CLASTREER.
